UNITED STATES PATENT OFFICE.

JOSEPH WELLINGTON BUCKLAND AND ROBERT McVICAR, OF MONTREAL, QUEBEC,
CANADA.

DRIFTING-VALVE.

1,284,952.

Specification of Letters Patent. Patented Nov. 12, 1918.

Application filed October 15, 1917. Serial No. 196,747.

To all whom it may concern:

Be it known that we, JOSEPH WELLINGTON BUCKLAND and ROBERT McVICAR, both of the city of Montreal, Province of Quebec, Dominion of Canada, both subjects of the King of Great Britain, have invented certain new and useful Improvements in Drifting-Valves; and we do hereby declare that the following is a full, clear, and exact description thereof.

In order to obviate any tendency for a vacuum to be created in the cylinders and steam chests of locomotives when drifting, the practice is to employ an automatically controlled auxiliary steam supply the essential operating element of which is usually an automatic differential valve. This valve stays open when the engine is traveling at a high speed, fifty strokes per minute or more for instance, and opens and closes intermittently when the engine is making less than fifty strokes per minute.

The effect which causes the valve to remain open is the exhausting influences exerted upon the upper side of the valve synchronously with the engine strokes, and with the exhaust acting with this frequency of fifty per minute the intervals of time between them are not of sufficient duration to permit the valve to close. Consequently although the valve may flutter in its full open position it will never appreciably diminish the flow of the auxiliary steam to the steam chests while it is needed to relieve a drifting engine having this relatively high speed. When the frequency of the exhaust drops however, owing to the slowing down of the locomotive, the intervals between the exhausts are of sufficient duration to permit the valve to close; and each time it closes there is a protraction beyond the actual interval between the strokes of the piston due to the fact that the pressure in the cylinder must be reduced to a degree lower than atmospheric before the valve opens. The object of the present invention is to increase the frequency of the exhausts exerted in the differential valve chamber, and thereby cause the valve to remain open practically until the engine is stopped. The result obtained is a substantially continuous supply of auxiliary steam during the movement of the engine at a very low speed.

The best practical results are obtained by our invention when the automatic differential valve above-mentioned is employed, the

peculiar construction of the differential valve proper and the contiguous portion of the valve casing wherein the steam admission port is contained forming a nozzle and causing the inflowing steam to create a suction thereon and immediately in advance of the said nozzle which suction is transmitted through the nozzle and an axial port in the valve to the upper side thereof. The inflowing steam is caused to impinge on the underside of the valve before exerting a suction influence on the nozzle. The effect is that an exhausting influence is caused on the greater differential face of the valve and simultaneously the impact of the auxiliary steam assists the exhausting influence in tending to keep the differential valve open even during the movement of the engine at a very low speed.

The invention may be said to consist of a unitary drifting valve including means whereby the valve proper when automatically opened will have a tendency to remain open owing to a peculiar construction and arrangement of the parts whereby the auxiliary steam from a unitary valvular means reaches a plurality of steam chests and through them relieves the disturbance in a plurality of cylinders due to the locomotive drifting, or, in other words running with the throttle closed.

For full comprehension, however, of my invention reference must be had to the accompanying drawings forming a part of this specification in which similar reference characters indicate the same parts, and wherein:—

Figure 1 is a fragmentary front elevation of an engine frame with our invention applied thereto;

Fig. 2 is a side elevation partly in vertical axial sectional view taken on line 2—2 Fig. 3; and

Fig. 3 is a similar sectional view taken on line 3—3 Fig. 2.

The casing of our improved distribution valve is formed with an upper cylindrical portion *b* and a bottom branched portion *c* presenting oppositely extending ends tapped to serve as pipe connections; a portion of this casing midway its height being of straight cylindrical form to constitute a valve seat *d* into which a vane *e* cast integrally therewith upwardly projects. This vane is of sufficiently less diameter than the seat to present a surrounding annular cham-

ber f and slightly above the bottom of this chamber it is surrounded by an annular port g with which is connected at h a pipe leading from the boiler. This casing is closed 5 by a cap l .

The automatic valve operating within this 10 chamber is of the differential type and preferably of inverted conoidal form, the apex of which is truncated and in the form of a nozzle which is surrounded by a cylindrical 15 valve k forming an integral part thereof the lower end m of which is of annular form and disposed with its bottom edge in line with the truncated apex of the nozzle n , the annular member m being connected to the nozzle by a web m' which is an integral part 20 of the nozzle and valve and constitutes with the edge of m and the apex of the nozzle the minor face of the differential valve proper. 25 This face has an annular concavity 50 encircling the nozzle and with which the annular vane e coincides. The inverted base p of the valve is of piston form and adapted to reciprocate in the cylindrical portion b 30 of the casing. This piston and valve k are provided with packing rings q . The lower end of the casing between the nozzle and valve and the bottom of the casing between the pipe connection branches is expanded 35 as at r . This automatic valve is chambered and provided with an axial port j .

Our improved valve is located between the steam chests as shown at b in Fig. 1 and a pair of steam pipes w connect the pipe 40 connection branches c to the steam chests and thence to the cylinders indicated at x at the opposite sides of the engine.

In order to provide a drain for the valve and at the same time the necessary atmospheric pressure communication, a drip pipe u connects an opening v in the valve casing below its cylindrical seat d and extends downwardly between the engine frames and to within a short distance of the rail level.

45

Operation.

In the operation of our invention, the engine being in motion, when the throttle is closed and the steam pressure in the main 50 valve chamber and cylinder drops below atmospheric pressure, the differential valve is lifted thus uncovering the steam port q and admitting auxiliary steam direct to the two steam chests simultaneously through pipes 55 w, w .

This flow of the steam from port q , the valve being at the top of its travel, first meets the vane e which deflects it upwardly against the top of the concavity 50 in the valve between the flange m and the nozzle n and the impact has a lifting effect. The steam is then deflected downwardly and follows the surface of the nozzle and is concentrated in a solid jet at a point immediately 60 beneath and in close proximity to the truncated apex of the nozzle and flows directly into the pipes w , the expanded port r affording ample clearance to prevent an accumulation of pressure at the apex of the nozzle and thereby avoid a back pressure of 70 steam through port j to the top and larger area of the valve. The effect is that a suction is exerted on the port j and consequently on the upper side of the valve while steam is flowing and this tendency to create a 75 vacuum assists in maintaining the latter in its lifted and open position. This advantageous result is due to the action of the steam by reason of the baffler-vane e , concavity 50, nozzle, port j , expanded port r and the fact 80 of the two steam pipes w leading to the two steam chests, being served.

An important feature of this beneficial result is that the automatic valve works more smoothly at slow speed by reason of the 85 division of the time of the exhausts. Our invention gives communication between both steam chests and consequently four centers of disturbance, and as each disturbance in the cylinder causes a movement of the differential valve and each revolution of the wheel of the engine causes four disturbances, by our invention connecting a single valve with a plurality of steam chests the exhausts 90 exerted on the differential valve proportionately measured in frequency, results in 95 smoothness.

Another advantage of the plurality of connections between the differential valve chamber and the plurality of steam chests is 100 that an open communication of full capacity constantly exists between the main valve chambers. The effect is that we practically prevent backing-up of the auxiliary steam in this main valve between the ports, this 105 backing-up being due to the retardation of the flow of the auxiliary steam because of the slow movement of the piston in the main cylinder, which has the disadvantageous effect of a backing-up pressure in the differential valve chamber thereby causing a 110 tendency of the differential valve to close when it should be open. By our connection of the differential valve to two or more steam chests this tendency to retard the flow of 115 the auxiliary steam is reduced to a minimum.

What we claim is as follows:—

1. The combination with a unitary drifting valve for the relief of locomotive cylinders, the casing thereof having an inlet for 120 drifting steam and such casing containing an automatic differential valve proper having a downwardly projecting nozzle and a concentric valvular member constituting the lower end of the valve and formed with a 125 concavity therein, the upper end of the valve being of greater area than the lower end and of piston form, and means effecting a constantly open communication between the upper and lower sides of the valve, of a con- 130

nection forming an intimate component part of the valve casing and having an annular baffle-vane accommodated within the annular concavity of the valve when the latter is closed and a twin pipe connection for communication with the cylinders at the opposite sides of the locomotive.

2. The combination with a unitary drifting valve for the relief of locomotive cylinders, the casing thereof having an inlet for drifting steam and such casing containing an automatic differential valve proper having a downwardly projecting central nozzle and a concentric valvular member constituting the lower end of the valve and formed with an annular concavity therein, the upper end of the valve being of greater area than the lower end and of piston form, such valve having an axial port there-

through and the casing having an opening to 20 the atmosphere below the said upper end of the valve, of a connection forming an intimate component part of the valve casing and having an annular baffle vane accommodated within the annular concavity of the 25 valve when the latter is closed and a twin pipe connection for communication with the cylinders at the opposite sides of the locomotive.

In testimony whereof we have signed our 30 names to this specification in the presence of two witnesses.

JOSEPH WELLINGTON BUCKLAND.
ROBERT McVICAR.
